PYRMA E. FISCHER, OF NEW YORK, N. Y.

CLEANING DEVICE.

1,081,597.

Specification of Letters Patent. Patented Dec. 16, 1913.

Application filed July 14, 1913. Serial No. 778,905.

To all whom it may concern:

Be it known that I, PYRMA E. FISCHER, a citizen of the United States, residing in the city of New York and State of New York, have invented a new and useful Improvement in Cleaning Devices, of which the following is a specification.

This invention relates to a device for washing dishes without handling a dish cloth or soap, or putting the hands in soapy water.

The device is especially adapted for use in connection with a rotatable soap holder which forms the subject matter of a separate application.

The invention consists in the novel features of construction hereinafter described, pointed out in the claims and shown in the accompanying drawings, in which:

20 Figure 1 is a plan view. Fig. 2 is a longitudinal section. Fig. 3 is a section on the line 3—3 of Fig. 1. Fig. 4 is a section on the line 4—4 of Fig. 2.

In these drawings 1 represents a shallow 25 cylindrical spraying nozzle, the underside and the top of which are concavo convex thereby adapting the nozzle to be inserted into a suitable dish holding frame and between the dishes, the outward bulging of 30 the under face of the nozzle and the inward depression of the top fitting the nozzle to accommodate itself to the shape of the usual dish. The under face of the nozzle is provided with suitable perforations 3 so 35 as to direct the streams of water forwardly toward a flattened nose 4 which projects from one side of the spray nozzle 1. This nose is also provided with suitable perforations 5 upon its under side. Opposite 40 the nose the spraying nozzle is provided with an inlet tube 6 and as the device may be frequently used with hot water and said tube might be raised to too great a temperature to make it convenient to use the tube 45 as a handle I place the handle members 7 upon opposite sides of said tube. A flexible hose section 8 is adapted to be connected to the tube 6 and conveys water thereto from any suitable source, said water being 50 preferably passed through my rotatable soap holding device before reaching the nozzle 1. The said nozzle would preferably be about five inches in diameter and possibly two or less inches in thickness. The top is pref- 55 erably threaded into the nozzle as shown. At the point of connecting the top 2 and the

nozzle the said nozzle is reduced in diameter so that when the top is placed in position a circumferential groove is formed about the nozzle and said groove is adapted to receive 60 a tape 9 the ends of which are connected to a dish cloth 10. Said cloth is in the form of a sleeve or finger and is adapted to be drawn over the nozzle 4, but fitting the same loosely so that it will hang from the side as 65 shown in Fig. 2 and is retained in place by means of the tape 9. By inserting said nozzle between the dishes they can be thoroughly sprayed and then can also be wiped by means of the nose 4 and the dish cloth 70 carried thereby, a continuous supply of water being discharged into the cloth through the openings 5. The nose 4 can also be employed for cleaning cups and glasses, or for cleaning corners in irregular shaped 75 dishes. After the washing operation has been completed the device can also be used for wiping the dishes by cutting off the water supply and replacing the wet dish cloth with a clean dry one. By means of 80 this device dishes can be thoroughly cleaned without putting the hands into the dish water or handling any soap, especially when used in connection with my soap holder above referred to.

85 What I claim is:

1. A dish washer comprising a hollow body having a laterally projecting nose, said body being perforated upon one side so as to direct streams of water toward said nose, 90 the said nose being perforated upon one side, a water inlet tube carried by said body upon the side opposite the nose, and means for securing a dish cloth upon said nose.

2. A dish washer comprising a shallow 95 cylindrical body having a perforated concavo convex bottom, a detachable concavo convex top carried by said body, a flattened nose leading from one side of the body a water supply tube opening into the opposite 100 side of the body, said nose being adapted to receive a dish cloth.

3. A device of the kind described comprising a shallow cylindrical body perforated upon one side and having a projecting perforated nose, means for admitting water into said body a fabric sleeve loosely closing the nose, said body having a circumferential groove, and a holding tape secured to said fabric and resting in said groove. 105

4. A device of the kind described comprising a cylindrical body the under face of

which is bulged outwardly, a detachable top depressed inwardly, said body being reduced in diameter adjacent said top thereby forming a circumferential groove when the top is 5 in place, a flattened nose projecting from one side of the body, the under face of the body and the nose having perforations directing streams of water in the direction of

the outer end of the nose, a water inlet tube carried by the body, and handle members 10 carried by said tube as and for the purpose set forth.

PYRMA E. FISCHER.
